(57) **CLAIM**

The ornamental design for a double wall cup with lid, as shown and described.

DESCRIPTION

FIG. 1 is a perspective view of a double wall cup with lid;
FIG. 2 is a front elevational view of the double wall cup with lid of FIG. 1 with the rear elevational view being a mirror image thereof;
FIG. 3 is a top plan view of the double wall cup with lid of FIG. 1;
FIG. 4 is a bottom plan view of the double wall cup with lid of FIG. 1;
FIG. 5 is a left side elevational view of the double wall cup with lid of FIG. 1;
FIG. 6 is a right side elevational view of the double wall cup with lid of FIG. 1;
FIG. 7 is an exploded perspective view of the double wall cup with lid of FIG. 1 showing an outer cup, an inner cup and a lid;
FIG. 8 is a partially exploded perspective view of the double wall cup with lid of FIG. 1 showing the inner cup nested within the outer cup;
FIG. 9 is a perspective view of the outer cup of the double wall cup with lid of FIG. 1;
FIG. 10 is a front elevational view of the outer cup of the double wall cup with lid of FIG. 1 with the left side, right side, and rear elevational views being identical to the front elevational view of the outer cup;
FIG. 11 is a top plan view of the outer cup of the double wall cup with lid of FIG. 1;

FIG. 12 is a bottom plan view of the outer cup of the double wall cup with lid of FIG. 1;
FIG. 13 is a perspective view of the inner cup of the double wall cup with lid of FIG. 1;
FIG. 14 is a front elevational view of the inner cup of the double wall cup with lid of FIG. 1 with the left side, right side, and rear elevational views being identical to the front elevational view of the inner cup;
FIG. 15 is a top plan view of the inner cup of the double wall cup with lid of FIG. 1;
FIG. 16 is a bottom plan view of the inner cup of the double wall cup with lid of FIG. 1;
FIG. 17 is a perspective view of the lid of the double wall cup with lid of FIG. 1;
FIG. 18 is a front elevational view of the lid of the double wall cup with lid of FIG. 1 with the rear elevational view being a mirror image thereof;
FIG. 19 is a left side elevational view of the lid of the double wall cup with lid of FIG. 1;
FIG. 20 is a right side elevational view of the lid of the double wall cup with lid of FIG. 1;
FIG. 21 is a top plan view of the lid of the double wall cup with lid of FIG. 1; and,
FIG. 22 is a bottom plan view of the lid of the double wall cup with lid of FIG. 1.
The dashed lines in the figures illustrate portions of the design that form no part of the claimed design.
